DISPENSING DEVICE

Johannes Henricus Maria van Doornik, Wassenaar, Netherlands, assignor to Johanna Margaretha Maria van Doornik, Wassenaar, Netherlands

Application April 21, 1952, Serial No. 283,364

Claims priority, application Netherlands October 23, 1951

5 Claims. (Cl. 222—386)

The invention relates to an incompressible tube with cap, e. g. for tooth-paste, paint, ointment or any other pasty material. It has for its object to provide a tube of a simple construction which is suitable for mass production.

According to the invention a piston or displacer is arranged in sliding fit engagement in the rigid tube body, e. g. made of plastic or any other suitable material, and the rigid tube cap, e. g. likewise made of plastic, wood, or any other suitable material, can be inserted in the open end of the body remote from the mouth of the tube to contact with the piston or displacer, in order to displace the same in inward direction.

According to the invention the outside diameter of at least part of the cap, preferably the lower end, with which the cap can be put or screwed on the mouth of the tube, may be almost equal to the inside diameter of the tube-body, so that the cap may be inserted in sliding fit engagement in the body of the tube in order to displace the piston in said body over the axial distance required for expelling part of the contents of the tube. Preferably the length of the cap will substantially correspond with the maximum distance over which the piston may be displaced from the end position when the tube is completely filled to the other end position when the tube is empty.

Because the cap itself is directly guided in the tube-body no separate guide members are required on the piston or the tube-body respectively for preventing the cap from jamming when the piston is displaced. The piston may, therefore, be a simple flat disk-like member and the tube-body may at the end remote from the mouth be simply open tubular; the open end may be flared.

The construction is extremely simple and suited for mass production at a low cost price.

When the tube is in its filled initial position the open end of the tube-body, then containing the piston, may be temporarily closed by means of an easily removable adhesive plaster or a similar means.

According to a specific embodiment of the principle underlying this invention the tube may according to the invention at the end remote from the mouth be provided with a detachable closure member having a central opening in which the cap may be inserted in sliding fit engagement and/or the piston or displacer may on the side which faces outwardly be provided with a centering means for an end of the cap.

The construction with a detachable closure member which e. g. may be screwed in and out, which closure member has a central guide opening for the cap, renders it possible by pressing the cap through said opening against the piston or displacer to expel the contents of the tube. The tube may be placed in an upright position resting on the closure member, said closure member may as a guide member for the cap be combined with a centering means on the piston, which centering means according to the invention may consist of a pen-shaped protrusion on the piston, or a recess in the piston over which or in which respectively, the cap may be slidably fitted.

According to the invention it is also possible to omit the closure member and only to use a centering means for the cap on the piston. For a proper central guiding when expelling part of the contents of the tube a relatively long protrusion on the piston may be used. The cap will preferably be as long or substantially as long as the tube-body so as to make it possible to completely expel the contents of the tube without it being necessary to insert

2

a finger in the tube-body. When the tube is completely empty the free end of the cap will be flush with or substantially flush with the end of the tube remote from the mouth, of, if use is made of a closure member, flush with the plane surfaced outside thereof.

The tube may be operated in a very easy manner and with one hand.

The nozzle of the tube will preferably be of the same diameter as the centering means on the piston or the displacer, so that the cap may then be easily put on the nozzle in sliding fit engagement.

The drawing elucidates the invention with some embodiments.

Fig. 1 shows a longitudinal section, partly in elevation, 15 of a tube with cap according to the invention.

Fig. 2 shows said tube with the cap inserted in the tube-body.

Fig. 3 shows a tube according to the invention, partly 20 in longitudinal section, partly in elevation, the cap being shown in two positions, viz. on the tube and inserted in the tube (indicated in dotted line).

Fig. 4 shows the tube in the position in which it is used, the cap contacting with the piston in the tube.

The tube represented in the drawing comprises a rigid 25 body 1 having a circular cross-section, which body is e. g. made of plastic and has a nozzle 2 provided with an external screw-thread, on which nozzle the lower end 3 of a rigid tube-cap 4, e. g. made of plastic, is screwed, which lower end is provided with a corresponding internal screw-thread. The outside diameter of the lower end 3 is substantially equal to the inside diameter of the tube body 1, so that the lower end 3 will slidably fit in the tube-body. The upper end of the cap has with a view to economizing on material a smaller diameter than the lower end 3. A disk-shaped piston 5 is provided in sliding fit engagement in the tube-body. The piston comprises a central pen-shaped part 6, which may be received with some play in a correspondingly shaped chamber 7 in the end of the tube-nozzle.

40 Fig. 2 shows how the cap 4 has displaced the piston 5 in inward direction over a certain axial distance.

The tube-body is at the open lower end at 8 somewhat flared in order to promote an easy insertion of the cap.

45 The length of the cap 4 is substantially equal to that of the tube-body.

The tube may be placed in upright position on the open lower end of the body.

According to the embodiment shown in Figs. 3 and 4 the tube comprises a cylindrical body 1 which via a 50 conical part 9 merges into a cylindrical nozzle 10 having a lateral outlet 11. A cap 12 is provided in sliding fit engagement on the nozzle 10 (Fig. 3). In the tube-body 1 a piston or disk-like displacer 5 is provided in sliding-fit engagement; said piston is on the outside provided with a central pen-shaped guide member 13, on which member the cap may be put in sliding fit engagement (vide the dotted position of the cap in Fig. 3). The open end of the tube-body is closed by means of an annular closure member 14 which with an external screw thread is 55 screwed in the internal screw thread of the tube-body. The closure member comprises a central opening 15 in which the cap 12 may be inserted in sliding fit engagement. Guide member 13 and opening 15 are co-axial. The cap 12 is substantially of the same length as tube body 1 with closure member 14. The nozzle 10, the opening 15 and the guide member 13 are substantially 60 of the same diameter as the bore in the cap 12.

65 A manner in which the tube may be held with one hand and in which at the same time the cap may be operated with a finger of the same hand to displace the piston for expelling part of the contents of the tube appears from Fig. 4.

70 It is evident that the invention except for a tube with a one-piece body likewise holds good for a tube with a body consisting of two or more longitudinal sections of the same or substantially the same length according to applicant's Dutch patent application No. 164,378.

75 I claim:
1. An incompressible dispensing tube for tooth paste, paint, ointment and other pasty material comprising, in combination, a rigid tube body having a neck provided

with a mouth for emission of the contents of the tube body and an opposite open end, a displaceable member adapted for sliding fit engagement interiorly of the rigid tube body, and an elongated rigid cap member having an end provided with a recess for receiving the tube neck for closing engagement therewith, said end of said cap being adapted to be inserted in the opposite open end of the body of the tube for contact with the displaceable member to displace said member in the direction of said mouth.

2. Tube with cap according to claim 1, characterized in that at least part of the rigid cap member has an external diameter which is substantially equal to the internal diameter of the body of the tube, so that the cap may be inserted in the tube body in sliding fit engagement.

3. Tube according to claim 1, characterized in that the displaceable member on the side which faces out-

wardly is provided with a protrusion which fits into the recess of the cap.

4. Tube according to claim 1, characterized in that the cap is of substantially the same length as the tube body.

5. Tube according to claim 1, characterized in that the neck of the tube is of the same diameter as the centering means on the displaceable member.
